DESIGN FOR A CIRCULATING GAS HEATER

William T. Bradbury, Palo Alto, Calif., assignor
to James Graham Manufacturing Co., San
Francisco, Calif., a corporation of California

Application September 8, 1937, Serial No. 71,505

Term of patent 7 years

To all whom it may concern:

Be it known that I, William T. Bradbury, a citizen of the United States and a resident of the city of Palo Alto, county of Santa Clara, State of California, have invented a new, original, and ornamental Design for a Circulating Gas Heater, of which the following is a specification, reference being had to the accompanying drawing, forming a part thereof.

Referring to the drawing:

The figure is a perspective view of a circulating gas heater, showing my new design.

The other end is the same as the end shown in this drawing.

I claim:

The ornamental design for a circulating gas heater, as shown and described.

WILLIAM T. BRADEBURY.
